UNITED STATES PATENT OFFICE.

IMMANUEL H. DIEHL, OF MILWAUKEE, WISCONSIN.

KNOCKDOWN BOAT.

Application filed July 19, 1926. Serial No 123,368.

This invention relates to knock-down boats.

Objects of this invention are to provide a novel form of knock-down or sectional boat which is formed of a plurality of main sections, said sections being adapted for assembly in a ready and easy manner, and adapted for storage by nesting one section within the other.

Further objects of this invention are to provide a novel form of knock-down boat in which the several sections are held together by means of longitudinally extending cables, and in which the adjacent edges of the section are interlocked and provided with resilient gaskets so that a water-tight and secure joint is attained.

An embodiment of the invention is shown in the accompanying drawings in which:

Figure 1 is a plan view of the boat with parts broken away;

Figure 2 is a side elevation with parts broken away;

Figure 3 is a fragmentary detail of an upper edge of the boat;

Figure 4 is a side elevation of the structure shown in Figure 3.

Referring to the drawings, it will be seen that the boat has been shown as composed of a central section 1, a front section 2, and a rear section 3, although, obviously, more sections could be employed, if desired.

The sections are provided with interlocking edges. For example, consider the central section 1. The rear edge of this central section is provided with an upper plate 4 and a lower plate 5, which are securely riveted or otherwise attached to the bottom and sides of the boat and thus form a continuous channel around the rear edge of the central section. Within this channel, a rubber or other yielding gasket 6 is positioned.

The rear section is adapted to fit within this channel, with its edges abutting the gasket. One of each of the adjacent sections is provided with an eyeletted member 7, which carries a looped link 8 in a pivotal manner. The outer end of this link is adapted to engage over the hooked end of a pin 9, as shown most clearly in Figure 4. Thereafter, the sections are rocked downwardly to compress the gasket 6.

The joint between the intermediate or central section and the front section is identically like the one just described. In order to hold the several sections in locked engagement, cables 10 extend around the sides and

along the bottom of the boat. These cables are attached at their front ends to eyeletted securing members 11. At the rear ends, the cables are each provided with an eye-bolt 12, which extends through a bracket 13. These eye-bolts are provided with rear nuts 14, which may be screwed inwardly to tension the cables 10.

In view of the locking link or latch 8 at the upper edge of the adjacent sections, and in view of the firmly tensioned cables 10, it is apparent that a very secure and reliable joint between the sections is attained, and that when the boat is assembled, it is a unitary structure and acts in all respects as if it were built in the usual manner, and not in separate sections.

It is apparent that the boat may be very readily stored or shipped by detaching the cables and the latching links 8. Thereafter, the sections may be nested one in the other, and the cables may be rolled up and dropped into the innermost section. A very compact structure results and one which may be easily transported.

It is to be particularly noted that the joints at the several sections are not called upon to bear the major strain, as the cables extend longitudinally of the boat and take up this strain.

Further, it is to be noted that the yielding or compressible gaskets 6 insure a water-tight joint. Further, the sections may not shift one with respect to the other in view of the tongue and grooved or socketed joint formed by the upper and lower plates.

It will be seen that a very simple and reliable type of knock down boat has been provided which may be very cheaply constructed, which may be stored in a small place, and which may be quickly assembled with a minimum of effort.

Although the invention has been described in considerable detail, such description is intended as illustrative rather than limiting as the invention may be variously embodied and as the scope of such invention is to be determined as claimed.

I claim:

A knock-down boat comprising a body portion formed of a plurality of sections, each of said sections having a bottom and side walls, each of said sections also having at one of its ends an upper and lower plate, said plates forming between them a channel for the reception of the adjacent edge of the next sec-

tion, a yieldable gasket located in each channel, pivoted links carried by the upper face of the side walls of each section adapted to engage pins carried by the upper face of the 5 side walls of the adjacent sections, whereby said sections may be rocked about their upper edges to cause engagement of their lower edges, and a plurality of longitudinally extending cables secured to the front and rear 10 sections by means of eyelets, the rear eyelets

terminating in shanks adapted to pass through brackets secured to said rear section, one of said cables being located below the bottom of the sections, and means for selectively tightening the cables.

In testimony that I claim the foregoing I have hereunto set my hand at Milwaukee, in the county of Milwaukee and State of Wisconsin.

IMMANUEL H. DIEHL.
